UNITED STATES PATENT OFFICE.

ALBERT C. CREHORE, OF TARRYTOWN, NEW YORK.

TELEGRAPHY.

SPECIFICATION forming part of Letters Patent No. 707,959, dated August 26, 1902.

Application filed October 21, 1901. Serial No. 79,385. (No model.)

To all whom it may concern:

Be it known that I, ALBERT C. CREHORE, a citizen of the United States, and a resident of Tarrytown, in the county of Westchester 5 and State of New York, have invented certain new and useful Improvements in Telegraphy, of which the following is a specification.

My invention relates to that class of telegraph apparatus known as "superposed-current" systems, wherein one class or set of messages or signals is sent over a wire by the use of momentary currents of short duration and sharply defined or having a high rate of change of electromotive force, while another 10 set of signals or messages is sent over the same wire or circuit by currents of longer duration or having a lower rate of change and upon which the momentary currents are superposed. In the following description the 15 momentary currents will be designated as "pulsatory currents," and the telegraph apparatus operated thereby will be called the "pulsatory-current side" of the system, while the transmission and reception of messages 20 effected by the use of the currents of longer duration will be described as effected by the use of continuous currents, and the apparatus using the continuous current will be called the "continuous-current side" of the 25 system. For the purpose of illustrating the invention it will be assumed that the signals sent by the pulsatory currents are each produced by a succession of such currents flowing continuously or uninterruptedly for a period 30 of time corresponding to the duration of the signal to be produced, although, as well understood in the art, each signal might be sent by two pulses only and separated by an interval of greater or less duration, during 35 which any change of electric condition takes place on the circuit. In this class of telegraphs it has been proposed to employ condenser-shunts containing the pulsatory-current 40 receivers and formed around a suitable reactance or inductance, the latter permitting the flow of the continuous currents but obstructing the flow of the pulsatory currents, while the condenser, on the other hand, affords a path for the pulsatory currents but 45 cuts off the flow of the continuous current. On the other hand, the pulsatory currents are

ordinarily prevented from acting upon the continuous-current receiver by shunting such pulsatory currents through a suitable condenser and by the reactance or inductance 55 in the branch containing said receiver. In most cases the transmitter for the continuous-current side of the system has been included in the branch with the continuous-current receiver, which, as stated, is shunted by a 60 condenser.

The objects of my invention are in general to avoid the disturbance or "kick" in the receiving instrument due to the discharge of the condenser or to the operation of any of the 65 keys or transmitters in the system, and also to so arrange the receivers for the pulsatory and continuous sides of the system respectively with relation to one another and to the transmitters for the two sides of the system 70 that they shall afford a minimum impedance to the flow of pulsatory current.

To these ends my invention consists, firstly, in the combination, with the continuous-current receivers and their condenser-shunts, of 75 protective non-inductive shunts properly adjusted to afford a ready path for any discharge current from said condenser following the charge of the same, either by the pulsatory currents or by the continuous currents. 80 By the use of this appliance I not only avoid any kick in the continuous-current receiver, but especially adapt the system to use for way-station work with a large number of stations, inasmuch as the non-inductive shunt 85 materially lessens the total resistance of the station apparatus to the flow of the pulsatory current and permits a large number of stations to be employed without requiring an electromotive force in the pulsatory-current 90 generator of prohibitive amount. Inasmuch as the flow of alternating current upon a circuit diminishes with the distance from the pulsating-current generator, I am enabled to sacrifice operating-current for those pulsating- 95 current receivers which are at the end of the line nearest the generator and where owing to the static capacity of the line the pulsating current is large and allow it to pass down to the more remote stations, where it would 100 be otherwise small, owing to the absorbing capacity of the line at the portion nearer the

pulsating-generator. Hence the line may be operated with a larger number of way-station apparatus or with a less strength of alternating current.

5 Another part of my invention consists in arranging the receivers for the pulsatory-current and continuous-current sides of the system in shunt to one another, the shunt or branch for the pulsatory-current receiver being made to include a condenser, and both shunts being free of the transmitting devices, which being placed at another point on the circuit do not cause any kick in the receivers through the opening and closing of the 15 circuit for the condenser in the branch containing the pulsatory-current receiver.

My invention consists, further, in the combination, with the pulsatory-current receiver and continuous-current receiver in shunt relation to one another on the circuit, of a condenser in the pulsatory-current branch and a non-inductive resistance in a shunt around the continuous-current receiver. By thus arranging the receiving apparatus at any 25 way-station when the station is not in use for transmitting messages I very materially reduce the total resistance of the circuit to the flow of the alternating or pulsatory currents, and thus very greatly increase the number 30 of way-stations that may be operated upon a circuit and for any given line reduce the strength of alternating current which it is necessary to use. It is well recognized that the difficulty in operating a telegraph-line, 35 especially when employing an alternating current, assuming that the insulation resistance is high, increases as the product of the resistance and the distributed electrical capacity increases. It does not make so much 40 difference how these two quantities are proportioned, provided we consider their product. For simplicity, consider the case of a line having only two stations, one at each terminal, equipped for duplex-diplex working. The effect of the distributed capacity 45 is to cause the alternating current to decrease rapidly as we proceed from the transmitting toward the receiving end of the line. To maintain a fixed current at the receiver, 50 which is that required to operate it, it is necessary to employ currents at the transmitting end, which become rapidly larger as the product of the resistance and distributed capacity 55 is increased; but the larger the current the greater the disturbance by induction upon neighboring telephone-lines, particularly at the end of the line where the generator is located, while, moreover, there is greater liability to disturbance of the Morse side of 60 the system from the action of the condensers used for the pulsatory-current side. If the attempt be made to overcome the difficulty by using lower frequencies, there is increased liability to disturbance between the two sides 65 of the system itself, since the currents employed for the two sides of the system are then less fully differentiated. My invention

overcomes the difficulties by making it possible to work the system with a less strength of current than would otherwise be required. 70

In the accompanying drawings, Figure 1 illustrates diagrammatically an arrangement of apparatus embodying my invention and shows the invention as carried out in a way-station system wherein the pulsating-current generator is located at one point and the signals are transmitted over the pulsatory-current side of the system from way-stations by suitably modifying the electrical condition of the circuit as to the flow of pulsating current. 80 Fig. 2 illustrates the application of my invention to a way-station system wherein way-stations are provided with pulsatory-current generators introduced into the circuit for the purpose of transmitting signals. Fig. 3 shows 85 another arrangement of the transmitters adapted for use in connection with the arrangement of receivers and generators illustrated in Fig. 1. Fig. 4 illustrates a modification in the arrangement of the pulsatory-current generator and transmitter at the terminal station. Fig. 5 illustrates a modification of the arrangement of devices for transmitting on the pulsatory-current side of the system, and Fig. 6 a modification of the 90 arrangement of apparatus for transmitting on the continuous-current side of the system. Fig. 7 shows in a simplified form the arrangement of Fig. 1 as it practically exists when two stations are transmitting simultaneously, 100 one by the continuous-current side and the other by the pulsating-current side, the parts which are short-circuited and which do not, therefore, offer any impedance being omitted from the diagram. 105

Referring to Fig. 1, I have shown the line provided with two terminal stations A W and a number of intermediate stations B C U V. My invention is, however, adapted for use with a very much larger number of intermediate stations, and I have in practice employed as many as twenty on the same circuit without difficulty. Inasmuch as one of the principal uses of my invention is upon circuits employing an ordinary Morse telegraph apparatus operated by continuous currents, I have shown the circuit as equipped with a Morse telegraph instrument of the usual character for the continuous-current side of the system. 110

3 indicates the Morse relays, and 5 the continuous-current generators supplying the current for operating said relays. 1 indicates the Morse keys controlling the flow of current from said generators in the usual way 115 over the circuit. For a closed-circuit system it will be understood that said keys are normally shunted by the usual circuit-closers 15 and that the current from the generators 5 flows over the circuit and through all the receivers 3, but that by opening the circuit-closer 15 for any key 1 a message may be transmitted by said key to be received on any 120 or all of the Morse relays 3. 130

6 indicates the pulsating-current generator, which operates to keep the line continuously charged with pulsating current, preferably a sine-wave current, for which purpose said generator 6 may be an alternating-current dynamo constructed to supply approximately sine-wave current. A pulsatory-current generator 6 is shown at each end of the line. In practice only one of them would be used at a time. The generator 6 at station A is shown connected into circuit by the use of switching appliances 24 of typical form, while the generator 6 at the opposite end of the line is disconnected. Both generators 5 are shown connected at opposite ends of the line by switches 25, although in way-station work the generator 5 at the same station with the pulsating-current generator being used may be removed from the circuit, leaving the generator 6 only in circuit. For closed-circuit working the pulsations of the generator are permitted to normally flow over the whole circuit and through the apparatus at all of the stations. Any form of transmitting apparatus for the pulsatory-current side of the system may be used. In Fig. 1 the apparatus for this purpose consists of transmitters 2, which operate to open and close a shunt formed around a suitable inductance 12 and containing a condenser 8. In Fig. 1 the inductance is in the branch or shunt containing the transmitter 1, but might be in a shunt or branch independent of said transmitter, as indicated in Fig. 3, or in any other desired relation. The inductance 12 may consist of a coil of wire wound on a core having a closed magnetic circuit, as indicated and as well understood in the art. The operation of the key 2 will alternately remove and insert the impedance or reactance afforded by this coil to the flow of pulsating currents, thereby causing the pulsating-current receiver to respond in the well-known manner. The keys 2 are also provided with the usual circuit-closers 15. In order that the impedance of the condenser and inductance used with the transmitting devices may be removed from the circuit when the apparatus is not in use for transmitting messages, but only for receiving, it is preferred to employ the shunting arrangement shown and consisting of the switch 15, that in addition to closing the circuit around the contacts of keys 1 2 also operates to complete a connection upon a supplemental contact 16. The contacts 16 being connected, as shown, and the devices arranged with relation to one another as indicated, it is obvious that when both switches are closed a complete short circuit will be formed around the inductance 12 and condenser 8 used in connection with keys 1 and 2. When, however, either switch is opened, the key with which it is associated may be employed in the ordinary way, and if both be in use the closing of the circuit-closer 15 associated with one key will not render the other key inoperative. This special arrangement

of devices is, however, claimed by me in the application in which I have set forth and claimed the special arrangement of keys 70 shown in this diagram.

4 indicates the pulsating-current receiver, which may be a short-core neutral relay, as well understood in the art, but is preferably a polarized receiving instrument, for the reason that a polarized receiving instrument is more sensitive to pulsating currents. Each receiver 3 is shunted by a condenser 8, and the pulsating-current receiver 4 is preferably arranged in the same shunt with the condenser, as shown. In a shunt around the receiver 3 is a non-inductive resistance 9 of such amount or value as to afford a ready path for the discharge-currents from the condenser 8, thereby protecting the instrument 85 3 from the disturbing effect of the condenser discharges. This shunt I term a "protective" or "compensating" shunt. It is of comparatively low resistance, as its function is not to open the line to the flow of the continuous current. With a relay of three thousand ohms resistance it might be of, say, four hundred ohms.

It will be noticed that the transmitters 1 are not in the shunt with the receivers 3, but are at points on the circuit outside said shunt, so that the instruments are less liable to disturbance upon the operation of the key and the discharge of the condenser in the shunt around it; also, the transmitter 2 for the pulsatory-current side of the system is in a shunt or branch independent of the branches containing the receiving instruments and for a similar purpose. This arrangement is of great practical importance, as it substantially eliminates the difficulties and disturbances in the action of the relays which would arise from the operation of the transmitters if the attempt be made to locate and operate them in the same branches with their receivers, respectively. The non-inductive resistance 9 at those stations nearer the pulsatory-current generator 6 has a greater shunting effect than those at stations more remote from the generator for the reason already stated—namely, 105 that owing to the static capacity of the line and its power to absorb the alternating current more current will flow on the portion of circuit near the generator, and there will be less effect from such current as the remote 120 end of the line is approached. Since then the actual amount of pulsating current is greater at stations nearer the generator, it is permissible to shunt current from the pulsating-current receivers at such stations and use 125 the shunted current to work the receivers more remote from the generator. By this means I am enabled to work the system with a larger number of way-stations and with a less electromotive force of pulsating-current 130 generator than would be the case if the device 9 were not employed. This device I term "inductance-load" or "retardation-coil." The non-inductive shunt 9, adjusted to have

the proper resistance for the action described, will with the arrangement of receivers shown, wherein the receiver 3 is in shunt to the condenser, have also the important function of diverting the discharge from said condenser following the charge of the same by the currents used on the system and will therefore protect the receiver 3 from disturbance. It will also protect said receiver 3 from the action of any transitory or variable currents arising from condensers, inductances, or other sources outside the receiver by affording a shunt-path or path of comparatively low resistance for them. The arrangement of the receivers in shunt relation to one another, as described, also serves to decrease the resistance of the station apparatus when not in use, and this resistance is further diminished by the presence of the non-inductive shunt 9 in multiple-arc relation to the other two branches containing the receivers 4 and 3. I claim herein, broadly, as my invention this arrangement of the receivers in branches which are shunts to one another and which are independent of the portions of circuit containing the transmitters, as shown in Fig. 1, but do not limit myself to the particular arrangement of the transmitters in branches in shunt relation to one another, as shown in said figure, since the value of the arrangement of the receivers may be realized with other arrangements of the transmitters—such, for instance, as the arrangement shown in Fig. 3.

The diagram Fig. 1 shows a line having two terminal and four way stations. The terminal stations are marked A and W, and the several intermediate stations are marked B, C, U, and V. A larger number of intermediate stations might be employed. Upon examination of the diagram it will be seen that the switch 15 for the continuous-current side of the system at station V is opened and the switch 15 for the pulsatory-current side of the system at station A is also opened. At all other stations the switches 15 for both keys 1 2 are closed, and the impedance afforded by the inductance 12 and condenser used in connection with the transmitters is removed from the circuit at said stations. The receivers 3 and 4, however, maintain their relation to the circuit, and each will respond to its own proper character of current. The pulsatory currents controlled by the transmitter 2 at station A flow over the whole circuit and operate all of the receivers 4 on the circuit, including that at station V, the action of the key being simply to open and close the shunt around the inductance 12 at station A and each closure allowing the pulsatory currents to flow freely over the circuit without encountering the impedance offered by the inductance 12. Said pulsatory currents flowing down the line operate upon all the receivers 4, even to the most distant. Similarly, any key 2 at any station may be employed in transmitting the signals by the pulsatory-current side of the system to sta-

tions farther down the line or toward station W. The operation of the key 1 at station V produces the usual effect of the Morse key 70 on the continuous-current circuit, and all the instruments 3 on the circuit shown will respond in obvious manner. The actual condition of the circuit as to impedance, &c., under the condition assumed for the switches 75 or circuit-closers can be more readily seen in the simplified diagram Fig. 7. With a line having a large number of stations equipped as shown it may not be found expedient to transmit from station W toward station A through any large number of stations by the use of the pulsatory currents generated at A. Under such circumstances and if it is desired to reach as far as station A by the pulsatory-current side of the 85 system the operator at W who wishes to use the pulsatory-current side may instruct station A on the continuous-current side of the system to remove the generator 6 from connection with the line at station A, and the 90 operator at W may then switch in his generator 6 and by operating his key 2 will cause the pulsatory-current receivers at all the stations on the whole circuit to respond, inasmuch as the flow of currents from said generator is completely cut off by the action of 95 said key. Also, as will be obvious, the operator at any intermediate station between W and A may transmit over the pulsatory-current side of the system effectually to all stations 100 in the direction of station A in a similar way, the generator 6 having been connected at station W and that of A having been removed. If the station is near W, the operator may also transmit to W and intermediate stations between his own station and W by modifying the pulsatory current of generator 6 at station W through opening and closing the shunt around the inductance 12, 105 as already explained. 110

I do not limit myself to placing the pulsatory-current generator at terminal stations on the circuit, as it may be placed at other points thereof and the flow of its current modified in the manner already described by 115 the action of the key 2.

While I have shown all of the stations similarly equipped in the diagram Fig. 1, some intermediate stations might be provided with apparatus designed to work only on the continuous-current side of the system, as indicated at station C in Fig. 3 of the accompanying drawings.

The combination of the special arrangement of transmitters shown in Fig. 1 with the 125 special arrangement of receivers shown in the same figure is not herein claimed, as it forms the subject of claims in another application for patent filed by me of even date herewith, Serial No. 79,383.

The shunting non-inductive resistance 9, employed as described, is especially valuable in connection with the relative arrangement of the receivers shown in Fig. 1, but may 130

also be employed with other arrangements of said receivers—as, for instance, in arrangements where the two receivers are located in series relation to one another on the circuit 5 and the receiver 3 is shunted only by the resistance 9.

In the diagram Fig. 2 I have shown two terminal stations A W and one intermediate station U all provided with apparatus for telegraphing both by continuous and pulsating current. At the terminal stations the transmitting apparatus for the pulsatory-current side of the system may be of any desired form, but is shown as comprising a key 2, 15 controlling the local circuit of a magnet, which operates upon a transmitter 2' of the continuity-preserving type and having its contacts connected, as shown, to the condenser in the shunt around the key 1 and to the pulsating 20 generator 6 in such manner that when the transmitter is opened the branch containing the condenser is closed directly to the continuation of the circuit leading to the generator 5 and earth. When the key is closed, 25 the direct connection is broken and the generator 6 is included in the branch with the condenser, so that the pulsatory current generated thereby will be caused to flow upon the circuit and operate upon the receivers for 30 the pulsatory-current side of the system. The transmitter 1 for the continuous side of the system is in the branch with the resistance 12, which latter operates to prevent the pulsating currents in the generator 6 from 35 flowing in short circuit when said generator is connected into the condenser branch. The transmitting apparatus at station U is of similar character, so that when the transmitter 2' is on its back stop the short circuit 40 through the condenser will be closed directly, but when on its front stop the direct connection formed over the back contact will be broken and a substitute connection through the front contact, including the pulsating- 45 current generator 6, will be formed, so that the pulsating currents from the latter will be supplied to the line and will affect all of the pulsatory-current receivers 4 on the circuit. A similar arrangement of devices to that 50 shown in Fig. 1 may be employed for cutting out the impedance of the condenser and inductance used in connection with the transmitting apparatus at the stations A U W or any stations similarly equipped. The circuit-closing switches 15, by which this is effected, are shown as used in connection with the transmitter 1 and with the key 2, which controls the transmitter 2', and is connected in a similar way to those shown in the diagram Fig. 1. Upon the closure of both circuit-closers 15 a shunt which short-circuits both the reactance 12 and the condenser 8 is formed over the contacts 16 of the circuit-closers. 65 Instead of connecting the generator 6 into circuit in the manner indicated in Fig. 2 it might be arranged as shown in Fig. 4, so that

when the transmitter 2' is on its back stop a branch circuit from the main line through the condenser is closed directly to earth; but 70 when the transmitter is on its front stop said direct connection is broken and a connection substituted from said condenser through the pulsatory-current generator, but not including the continuous-current generator, as 75 would be the case with the arrangement shown in Fig. 2.

Other way-stations upon the circuit, Fig. 2, may obviously be provided with continuous-current apparatus—as, for instance, stations 80 B, C, and V. In each of these cases an artificial shunt containing a condenser 8 and an inductance 12' is provided, said inductance taking the place of the inductance afforded by the receiver 4 at stations A U W and others similarly equipped. The inductance 12' should be adjusted so as to balance by its reactance the opposing reactance of the condenser and to thereby furnish at the stations B C V a ready path through said stations for 85 the pulsatory current at all times. This inductance 12', as described in another application for patent filed by me of even date herewith, Serial No. 79,387, wherein I claim the balancing of the condenser capacity or 90 reactance by the reactance of an inductance both arranged in the shunt to the continuous-current receiver 3, preferably consists of a coil wound upon a core which has a magnetic circuit of iron completely closed, excepting 95 at one or more points, where a narrow or thin break is afforded by an air-gap or similar break in the magnetic continuity of the iron circuit. Said inductance might, however, be of other form. The transmitter 1 at each of 100 the way-stations operates to break and close the circuit for the continuous currents, while the shunt containing the condenser 8 affords at all times a path for the pulsatory current. The non-inductive shunt 9 at said stations 105 B C V has the function already described.

In Fig. 3 the arrangement of receivers herein claimed is shown as applied on a circuit having a different arrangement of the transmitters. In this arrangement the line is 115 shown provided with transmitting and receiving apparatus for both the pulsatory and continuous current side of the system at stations A, B, V, and W, A and W being terminal stations. One intermediate station C 120 is shown provided with apparatus working on the continuous side of the system only, although a larger number of stations like C or like B might be employed on the circuit. In general it is preferable to use at all stations equipped with pulsatory-current apparatus suitable continuous-current apparatus, also to permit the operator receiving on the pulsatory-current side to break the distant transmitting-station when the pulsatory-current generator is at some distance from the receiver-station, so as to make it difficult to 125 reach the transmitting-station on the pulsatory-current side by reason of the absorbing 130

capacity of the line for the pulsatory currents. In the diagram Fig. 3 the pulsatory-current generator furnishes to the whole line a pulsatory electromotive force. Said generator might be, however, at some other station than station A. The transmitters for the pulsatory and continuous current sides of the system are here shown as arranged in series relation to one another instead of shunt relation. Each transmitter 1 for the continuous-current side of the system is adapted to make and break the shunt around a condenser 8, thereby practically opening and closing the circuit for the continuous currents, while each transmitter 2 for the pulsatory-current side of the system operates to make and break a shunt around the inductance 12 of high reactance and low resistance, thereby throwing said reactance into and out of the circuit, so as to alternately permit the pulsatory currents to flow and to stop their flow. This reactance ordinarily being of low ohmic resistance, permits the continuous current to flow readily. In cases where the circuit is short or the number of stations equipped with continuous-current apparatus is small the operation of the key 2, if connected in a direct shunt across the terminals of the inductance 12, might by shunting the resistance of 12 produce a false signal in the continuous-current receivers 3. To obviate such disturbance upon the continuous-current side of the system through variations of impedance introduced by the action of the key 2, a condenser 8 may be included in the shunt with it around the inductance, as shown in Fig. 5. The shunt, however, even with the condenser in circuit, will still allow the pulsatory current to flow when the key is closed, while the continuous current will at all times find a path through the coils of inductance 12. Inasmuch as the shunt containing the key is at all times open to the continuous current through the presence of the condenser, no disturbing effect upon the continuous-current side will be produced by the operation of said key. In circuit with the condenser 8, placed in shunt to key 1, as shown in Fig. 3, there may be provided a reactance, as indicated, consisting of an inductance 12', adjusted to balance the reactance of the condenser 8, and thereby permit the pulsatory current to flow more freely through said branch or shunt. For a reactance used in this relation I prefer to employ the form which is described and claimed in another application for patent filed by me of even date herewith, Serial No. 79,387, and which in the shunt to the key has the additional function of preventing sparking at the contacts of the key. The reactance-coil is wound upon a core whose magnetic circuit is closed excepting for the presence of a narrow gap (indicated at 20) consisting of air or other non-magnetic substance.

When the total impedance of the circuit to alternating currents is small, disturbance or change of impedance on the alternating-current

side of the system by working the key 1 may be avoided by introducing a reactance 12 into the shunt or branch containing said key, as indicated in Fig. 6. This inductance should have a high reactance or impedance and low ohmic resistance. It serves to block off the flow of the pulsatory currents through the shunt controlled by the transmitter 1 effectually, so that the impedance to the flow of the pulsatory currents remains the same whether the key be opened or closed in the operation of transmitting a signal. Hence no disturbance in the impedance to the flow of said pulsatory currents at the transmitter occurs when the signals are being transmitted on the continuous-current side. The circuit-closer 15 preferably in this case closes circuit upon a contact which is connected to the front anvil of the key and the inductance 12 remains in circuit when the key is out of use. When the Morse key is opened, the only remaining path for the alternating current is through the shunt. Sometimes there is no load or retardation coil required in series with the Morse key and in other cases it is required. If the line has a large number of stations with Morse relays, which are really equivalent to load-coils, and also has small distributed capacity, these coils are not required; but for the present purpose let us consider a two-station line only where these coils are used. It is very objectionable to have the working of the Morse key cause any effect upon the alternating-current relay in the line. It will do this (with a certain adjustment of the relay) if the value of the alternating current flowing is at all disturbed by the opening and closing of the key. For simplification suppose that there is no line between the terminal stations, but that the circuits have no balancing-coils with the condenser around the keys. If an ammeter is placed in the relay-circuit 4, the alternating-current generator being continuously in the line, the current in 4 will rise when 1 is opened and fall when 1 is closed, the generated electromotive force being constant. This result is surprising when first considered, as it is natural to expect that the closing of the key reduces the total impedance of the line, and thus increases the current in 4. When the proper coils are inserted in the condenser-shunt around the keys 1, it will be observed that when their inductance is larger than the proper value the current in 4 rises upon closing the key 1 and falls upon opening it. This is exactly opposite from the previous effect before the coils were inserted. It is evident, therefore, that there must be some value for the inductance of the coils, which will make it possible to operate the keys 1 without either increasing or decreasing the current in the alternating-current relay. This is approximately the balancing value for the condenser and may be most accurately obtained by adjusting until no effect on the alternating current is observed. It would be neces-

sary to resort to vector diagrams, which obtain when sine-waves are employed, to explain this result.

With the arrangement shown in Fig. 3 the circuit-closer 15 for the pulsatory-current side of the system may be opened and the transmitter 1 used for transmitting signals over the pulsatory-current side, as already described, and simultaneously or not with the operation of the transmitter 2 for the pulsatory-current side of the system at the same station or at any other station, its switch for the circuit-closer 15 having been also opened. The receivers 3 and 4 for all stations on the circuit will respond to the operation of said keys, as already explained. At the way-station C, where continuous-current apparatus only is shown, the receiver 3 has a shunting non-inductive resistance 9, and a shunt is provided which electrically is the same as the shunt containing the pulsatory-current receiver and condenser at other stations. In the shunt at C the condenser 8 is included in circuit with a suitable inductance 12', as already explained, which represents the reactance of the receiver 4 at other stations where receivers are provided for both sides of the system. This inductance balances by its reactance the reactance of the condenser 8 and assists the flow of the pulsatory currents through the station C. The inductance, which is preferably of the form already described as here used and as used in the shunts in connection with the transmitters 1 and 2, is claimed, broadly, in another application for patent filed by me of even date herewith, Serial No. 79,387. The transmitter 1 at station C acts, as already explained, to simply open and close the circuit to the flow of the continuous currents. The manner of transmitting by the pulsatory-current side through the operation of a key which shunts a reactance or inductance and the system of way-station telegraphy illustrated in Figs. 1 and 3, involving the use of pulsatory-current generators at terminals of the line, are not herein claimed, as they form the subject of claims in my application for patent filed by me of even date herewith, Serial No. 79,384.

My invention is obviously applicable to systems wherein the transmitting appliances are arranged in still other ways and also as to some of its features to systems wherein the transmitters and receivers for the two sides of the system, respectively, are arranged in still other relations to one another and to the circuit.

What I claim as my invention is—

1. In a superposed-current telegraph, the combination with a continuous-current receiver and pulsating-current receiver in shunt relation to one another upon the main line as described and having a condenser in the branch containing the pulsating-current receiver, of transmitters for the two sides of the system placed in branches or portions of

the circuit independent of the branches containing said receivers.

2. In a superposed-current telegraph, the combination of a continuous-current receiver in a shunt or branch of the main line, a pulsatory-current receiver in a shunt or branch of the main line, a condenser in said main-line shunt, and a transmitting apparatus for the continuous-current side of the system in a branch or portion of the circuit outside of both receiver branches.

3. In a superposed-current telegraph, the combination substantially as described upon the same line, of means for producing pulsatory currents for sending one class of signals over said line, pulsatory-current receivers for said signals, continuous-current receivers for the continuous-current side of the system, and branches around the coils of said continuous-current receivers forming non-inductive shunts of comparatively low resistance, as and for the purpose described.

4. In a pulsatory-current telegraph, the combination of a continuous-current receiver in a branch of the circuit continually closed, a shunt to said receiver containing a pulsatory-current receiver and condenser, and a non-inductive resistance in multiple-arc relation to the branches of the circuit containing respectively said pulsatory-current and continuous-current receivers.

5. In a superposed-current telegraph, the combination of a pulsatory-current receiver and a continuous-current receiver in shunt relation to one another, a condenser in the branch with the pulsatory-current receiver and a non-inductive resistance in a shunt around the continuous-current receiver.

6. In a superposed-current telegraph, the combination with the continuous-current receivers, of non-inductive protective shunts connected directly around the receiver-coils and of comparatively low resistance as described so as to protect the said receiver from the disturbing action of pulsatory or variable currents and to also permit the system to be operated with pulsatory currents of comparatively small strength, as and for the purpose set forth.

7. In a superposed-current telegraph, the combination with the continuous-current receivers and their condenser-shunts for the pulsatory currents, of protective non-inductive shunts for said continuous-current receivers adapted to shunt the condenser discharge and to permit pulsatory current to flow down the line to the more distant stations.

8. In a superposed-current telegraph, the combination with a continuous-current receiver and a condenser in shunt to the same for forming a path around said receiver for the pulsatory-current side of the system, of a protective non-inductive shunt to said receiver adapted to form a diverting path for the discharge of the condenser whereby said

receiver may be protected from disturbance from the condenser discharge.

9. In a superposed-current system of telegraphy, receiving apparatus for the continuous and pulsatory current sides of the system comprising a pulsatory-current receiver and condenser in one branch of the circuit, a direct-current receiver in a branch forming a shunt to said pulsatory-current receiver and condenser, and a compensating shunt around the direct-current receiver adapted to afford a path for diverting the discharge-currents of the condenser around the said direct-current receiver, as and for the purpose described.

10. In a superposed-current telegraph, the combination with a pulsatory-current generator adapted to generate electromotive force of the sine-wave type, a continuous-current receiver, a non-inductive shunt to said receiver, a continuous-current transmitter in the main line outside of the said shunt, and a shunt or branch around both the transmitter and receiver containing a condenser and an inductance.

11. In a superposed-current telegraph, the

combination with the continuous-current receivers at a way-station, of an artificial shunt containing a condenser and an inductance in series with one another.

12. In a superposed-current telegraph, the combination with the continuous - current transmitter and receiver apparatus at a way-station, of an artificial shunt taken around both the transmitter and the receiver containing a condenser and inductance in series with one another.

13. The combination in a superposed-current telegraph with the continuous-current transmitter, of a shunt thereto containing a condenser and inductance and an artificial load-coil in the branch with the transmitter for interposing artificial inductance when the key acts to shunt the branch or shunt containing the condenser.

Signed at New York city, in the county of New York and State of New York, this 16th day of October, A. D. 1901.
